UNITED STATES PATENT OFFICE.

ROBERT S. GRAHAM AND WILLIAM B. SAVELL, OF NEWARK, NEW JERSEY.

TYPE-WRITER-KEY CUSHION.

SPECIFICATION forming part of Letters Patent No. 532,153, dated January 8, 1895.

Application filed March 14, 1894. Serial No. 503,637. (No model.)

To all whom it may concern:

Be it known that we, ROBERT S. GRAHAM and WILLIAM B. SAVELL, citizens of the United States, and residents of Newark, in the 5 county of Essex and State of New Jersey, have invented certain new and useful Improvements in Type-Writer-Key Cushions, of which the following is a specification.

Our invention relates to keys or elastic 10 cushions adapted to be fitted to the keys of type-writing machines, cash registers and other mechanisms on which keys are to be employed, which are to be rapidly and often struck by the fingers; the object being to relieve the fingers of the operator from soreness, caused by striking the unyielding surfaces of ordinary keys.

Our invention consists in a socket adapted 15 to fit over the ordinary key, which socket is connected with an upper surface to receive the stroke of the finger, which upper surface is yieldingly supported by an elastic member interposed between it and the top of the key, and guided vertically by an upward 20 prolongation of the socket.

This invention may be applied in various 25 forms, of which several modifications are shown in the accompanying drawings, Figures 1, 2, 3, 4 and 5, each of which shows a vertical 30 section through the key and cushion of a separate modification.

Similar letters in each figure denote corresponding parts.

a is the ordinary typewriter key. 35 b is a cylinder open at the bottom. That part of which below the line x in each figure constitutes the socket receiving the key. This socket we prefer to provide with a lug or projection, as c, turned under the key-head to 40 prevent the socket from slipping off upward.

The top opening of the cylinder b is closed by a plate d which, in Figs. 1, 2 and 3, is formed in one piece with the cylinder, but in 45 Figs. 4 and 5 constitutes a disk separate from the cylinder and held within it by the overlapping flange e.

The cylinder b is longer than the key-head a and therefore, a space exists between the top side of the key-head and the under side 50 of the plate d.

Thus far, nothing has been described which would prevent the plate d from dropping down and resting directly on top of the key-head so as to prevent any range of elastic movement between the two. To prevent this 55 and maintain the space between the plate d and the top of the key-head, we interpose an elastic or resilient member which may be of various equivalent forms of construction. Thus, in Fig. 1, it consists of the helical spring 60 f which, at the top, rests directly against the under side of the plate d and at the bottom rests directly against the top of the key-head. In Fig. 2, it consists of a similar helical spring f which, however, is at the bottom separated 65 from the top of the key-head by a disk g loose within the cylinder b. As the heads of type writing machine keys differ somewhat in shape, some being flat on top and others hollowed out or dished, the cushions will be 70 constructed to meet such variations. When the key head is hollowed out, as in Fig. 2 it will be advisable to use the disk g as the same forms a better seat for the spring than would the hollowed out surface of the key-head. 75 In Figs. 4 and 5 the elastic or resilient member consists of a similar helical spring f resting against the key-head at its bottom, but the plate d instead of being in one piece with the cylinder b so as to compel the two to move 80 together, is separate from the cylinder b and may move within the same; the cylinder b serving to guide it and maintain it in its normal position. In this case, the internal diameter of cylinder b above the key-head need 85 not be as great in diameter as the portion of cylinder b forming the socket for the key-head. It may be as shown in Fig. 5.

In Fig. 3, the resilient member consists of a filling of hair or analogous elastic material 90 i between the plate d and the key-head a.

It will be observed that in each of the forms shown, the part b performs the function of a cylinder or guide within which the plate d and the key-head a may approach each other 95 in antagonism to the elastic member and recede from each other in obedience to the elastic member.

In the case of Figs. 1, 2 and 3, the key-head a is like a stationary piston within the mov- 100

ing cylinder *b*; whereas, in Figs. 4 and 5, the plate *d* is like a moving piston within the stationary cylinder *b*.

We claim—

5 A key cushion adapted to be fitted over a key and consisting of a cylinder *b*, the touch plate *d* and the resilient member arranged substantially as described, whereby the cylinder *b* acts as a guiding cylinder within 10 which the plate and the key may reciprocate

relatively under the impulse of the touch and the resilient member, as set forth.

Signed at New York, in the county of New York and State of New York, this 2d day of March, A. D. 1894.

ROBERT S. GRAHAM.
WILLIAM B. SAVELL.
